INSERT APPARATUS FOR OIL WELL
CASINGSReuel Francis Mackin, Wink, Tex., assignor to
Lamtex Equipment Corporation, Fort Worth,
Tex., a corporation of Texas

Application June 2, 1943, Serial No. 489,328

18 Claims. (Cl. 103—179)

1

This invention relates to methods and apparatus for use in the flowing of oil wells through the well casing instead of through tubing located inside the casing.

An object of my invention is to provide a method and apparatus which make it economical and practical to eliminate or salvage the tubing of an oil well and to use the well casing for conducting oil to the ground surface without losing the advantages of conventional installations in which tubing is employed.

Another object of this invention is to provide a casing pump apparatus for oil wells which enables the pumping element to be removed from the well for servicing, repair or other use, in the same manner as the pump element of conventional tubing pumps.

Another object is to provide a casing pump apparatus which will hold a column of oil in the casing at all times and yet permit the pump element to be withdrawn from the well whenever desired without dumping the column of oil above the apparatus back into the oil-bearing formation.

A further object of this invention is to provide a method and apparatus by which to locate and seal a casing pump unit at its pumping position in an oil well casing by manipulations of a string of sucker rods without danger of dropping the unit into the formation.

According to my invention I make a special casing pump installation in a new way and then flow oil from the formation through the well casing by the operation of this installation, in general as follows: I use a reciprocating pump element of any suitable construction, such as a plunger carrying a traveling valve of the kind heretofore used with tubing pump installations. I provide a special casing pump unit which is constructed so as to be located and sealed at a pumping position in the well casing and thereafter to receive and work with this pump element to force oil upwardly through the casing. And I provide a new insert device which is used in combination with the pump unit and with a string of sucker rods so as to locate and seal the unit in place in the casing and then to disconnect the unit and make it ready to receive and work with the pump element. After these operations, the rods and insert device are withdrawn from the well, the insert device is removed from the rods and replaced by the pump element, and the pump element is lowered by the rods to its working position and then operated inside the sealed pump unit. At any time thereafter the pump element

can be withdrawn for service or repair without disturbing the casing pump unit or affecting its seal or dropping the oil in the casing back into the well formation.

My invention therefore is particularly valuable for the flowing of low volume or low fluid level oil wells, which heretofore have had to be worked with internal tubing and tubing pumps to avoid dumping the oil into the formation whenever the pump required mechanical service or repair. By the use of this invention the tubing of existing well pump installations may be salvaged and used for other purposes, and newly developed wells may be pumped without the need of tubing to conduct the oil to the ground surface.

The foregoing and other objects, features and advantages of my invention will become more apparent from the following detailed description of an illustrative embodiment thereof, when considered in connection with the accompanying drawings. The new features of construction and operation which I claim as my invention are set forth particularly in the appended claims, which contemplate various modifications of the illustrative embodiment and are not restricted thereto except as may be required by a fair interpretation of their terms.

In the drawings:

Figures 1 and 1a are longitudinal views, partly in cross-section, showing upper and lower portions, respectively, of an assembly of a casing pump unit, an insert device and a string of sucker rods as the unit is located in a well casing ready to be sealed to the casing;

Figures 2 and 2a are longitudinal views, partly in cross-section, showing upper and lower portions, respectively, of the casing pump installation in its operating condition;

Figure 3 is an enlarged longitudinal section through a two-part mandrel which forms part of the assembly as the pump unit is lowered into the casing and located and sealed in pumping position; and

Figure 4 is a side elevation of the insert device as disassembled from the pump unit and sucker rods.

The drawings illustrate that portion of an oil well casing 10 in which it is desired to locate a pump mechanism to flow oil from the well. It will be understood that the oil-bearing formation lies adjacent to the bottom of the casing portion shown in Figures 1a and 2a, and that the well casing extends far above the top of the casing portions shown in Figures 1 and 2, to the

ground surface where suitable machinery is provided to operate the pump.

The main elements of the assembly of Figures 1 and 1a comprise a casing pump unit C, a string of sucker rods A, and an insert device B which interconnects the pump unit with the sucker rods. The main elements of the operating assembly in Figures 2 and 2a comprise the same casing pump unit C, the sucker rods A and the reciprocating pump element which in Figure 2a is marked with in the bracket D and is secured to the lower end of the rods.

By the term casing pump unit I refer to the structures which cooperate with the reciprocating pump element D. These may be of various forms, but essentially include a standing valve 20, a pump barrel 24 thereabove, and a casing pump head provided with means, such as an expandable packer 30 and a cooperating mandrel element 32, to be operated by the manipulation of rods A and insert device B to seal the pump unit in its working position. In addition, where the unit is not to be supported by structure provided for that purpose in the well formation, an anchoring means 40 of any suitable construction is provided as part of the pump unit for operation to anchor or locate the unit in place before flowing the well.

The operation in general is as follows: At the top of the well the pump unit C is assembled with the sucker rods A through the insert device B, which is positively yet releasably connected at its lower end to the top of the unit, such as by a special construction of the mandrel hereinafter described, and which is secured at its upper end to the lowermost sucker rod. This assembly is then lowered into the well casing until the unit has reached the desired pumping position. The rods are then turned, usually in a counterclockwise direction, to set the anchoring device 40 against casing 10 in a well-known manner. At this stage the mandrel element 32 is spaced above the packer 30, by reason of an interconnection which permits a limited relative axial motion between these parts. When the unit has been located in place by the setting of the anchor, the rods A are further lowered until the mandrel element 32 moves into the packer 30, and the rods are then manipulated up and down to operate the insert device B and pound the mandrel element tightly into the packer, thus sealing the unit at the packer against the well casing. This manipulation is provided for by the construction of the insert device, which includes a plurality of parts interconnected through a slip joint for limited relative movement in axial direction. After the unit thus has been sealed, the sucker rods are again turned, but this time in a clockwise direction, so as to disconnect the insert device from the unit at the top of the mandrel element 32, whereupon the rods and the insert device are withdrawn from the well. The insert pump element D is then secured to the rods A in place of the insert device B, and the pump element and rods are lowered into the well until the pump element has passed freely through the upper portion of the pump unit and reached its working position in the pump barrel 24. This is the operating condition depicted in Figures 2 and 2a. The rods are now reciprocated to operate the pump in its working barrel, with the effect of raising oil through the standing valve 20 into the pump element within the barrel and then forcing the oil through the travel-

ing valve of the pump element into the well casing and thence to the ground surface. The permanent standing valve 20 and the seal formed by packer 30 hold the column of oil in the casing 10 at all times, and the pump element D may be withdrawn from the unit at will without dumping this oil into the formation.

Referring more specifically to the illustrated form of construction, Figure 1a shows a nipple 14 at the bottom of the pump unit, through which oil is drawn from the formation, and the standing valve 20 is connected above this nipple. The pump barrel 24 extends above the standing valve and has between itself and the valve a seat 22 to limit the downward motion of the pump element D in its working barrel. The anchor 40 is secured to the top of the pump barrel through suitable tubular means, and similar means connect it rigidly with an outer or drain sleeve 26 of the casing pump head, shown in Figure 1. The annular expandable packer 30 is fastened to the top of the drain sleeve 26, and the mandrel element 32 is fixed to the top of a drain tube 28 that extends inside the drain sleeve and is connected therewith by suitable means, such as a tongue 29 working in a slot 27, for limited relative movement in axial direction.

It will be understood that when the casing pump unit as thus described is suspended in the casing from the mandrel element 32, the tongue 29 abuts against the top of slot 27 and the mandrel is located above the packer 30. In this condition of the unit, which exists before it is located or sealed in the well, a pin 41 of the anchoring device 40 will be located in a slot 42 so that the working elements of the anchor are retracted away from the well casing.

The mandrel of the assembly, as seen in Figures 1 and 3, is a novel two-part structure including element 32 as the lower part and an upper disconnectable part or cap 38 which is also a part of the insert device B. The lower part 32 has a conical or tapered outer surface 34 adapted to fit into and expand the packer 30, and is secured by conventional screw threads to the top of the drain tube 28. This mandrel element is hollow and open or flared at its top 36 to permit free passage therethrough of a pump element D fitting the pump barrel 24. The upper part or cap 38 is fitted to the lower part through mating means, such as a tongue 39 on the cap engaging in a notch 37 in the top part 36, to prevent relative turning motion but allow axial separation of the two mandrel parts. Both parts are threaded internally with registering left-hand screw threads 36a and 38a.

A coupling device 44 having external left-hand screw threads 44a is located inside the cap 38 with its threads in engagement with the threads 36a and 38a, as shown in Figure 1. The two mandrel parts thus are positively secured together during the lowering, location and sealing of the pump unit in the well. A stem 46 on coupling member 44 extends through and beyond the cap 38 and completes the lower part of the insert device B. This stem is tubular in form, and an upper tubular part 48 of the insert device is telescoped thereinto and connected therewith for limited relative axial movement, for example, through a tongue 49 on part 48 working in a slot 47 in part 46. The top of part 48 is secured to the lowermost sucker rod A.

The pump element D (Figure 2a) includes a suitable seating device 50 having rings to seal

against the inside of the working barrel and having a hollow stem 54 to rest in the seat 22 at the lower end of the working barrel, together with a reciprocating insert pump 56 of known construction above this seating device which pump has a part connected to the seating device by a tube 52 and has a traveling valve 58 at the top where the sucker rods A are attached.

When the insert device is disassembled from the pump unit and the sucker rods, as illustrated in Figure 4, it comprises the upper and lower telescoped parts 48 and 46 connected together through the slip joint 47 and 49, together with the coupling member 44 at the lower end of part 46 and the upper mandrel part or cap 38 threaded thereon.

When the insert device is assembled in preparation for locating and sealing the pump unit in the well casing, the cap 38 is fitted to the lower mandrel element 32 and the device is turned counterclockwise so as to engage the coupling member 44 with the screw threads 36a.

Upon lowering the assembly into the well, the pump unit and insert device are suspended from the sucker rods A with tongue 49 of the slip joint at the top of its slot 47 and with tongue 29 of the connection between the drain tube and drain sleeve at the top of its slot 26. The mandrel thus is located above the packer 30, and pin 41 of the anchoring device 40 is held in its slot 42.

When the pump unit reaches the desired pumping position, the rods A are first turned in a counterclockwise direction to free pin 41 from slot 42 and thus set the anchor against the well casing, which locates and holds the unit in the well. The rods are then lowered further to drop the tapered surface 34 of the mandrel into the packer, and are then reciprocated through the slip joint 47, 49 to pound the lower mandrel element into the packer and seal the unit against the casing. This having been done, the rods are now turned in a clockwise direction, whereupon the coupling member 44 is screwed upwardly into cap 38, out of engagement with the threads 36a on mandrel element 32, so that the insert device and rods are disconnected from the sealed pump unit and the latter is made ready to receive the pump itself for operation to flow the well. When the insert device has been withdrawn from the well and replaced on the rods by the pump element D, the pump element is lowered to its working position in pump barrel 24 and then reciprocated to flow the well.

I claim:

1. Apparatus for flowing an oil well through the well casing comprising a standing valve, a pump barrel thereabove, a drain sleeve connected above the barrel and having an annular expandable packer at the top, a drain tube connected with the drain sleeve for limited relative axial movement, a two-part mandrel including an upper part, a lower hollow part which is normally open at the top, has a conical periphery and is secured to the drain tube to move therewith and expand the packer, and means operated by turning the upper part to disconnect the two parts of the mandrel.

2. Oil well casing pump apparatus comprising the combination of a casing pump unit with an insert device for positively yet releasably connecting the unit with a string of sucker rods and operable by manipulation of the rods to locate and seal the unit at a pumping position in the well casing, said device comprising a plurality of parts connected together for limited relative ax-

ial motion, and said unit comprising an expandable packer and a cooperating mandrel having a releasable screw connection with the lowermost of said parts.

3. Oil well casing pump apparatus comprising the combination of a casing pump unit with an insert device for positively yet releasably connecting the unit with a string of sucker rods and operable by manipulation of the rods to locate and seal the unit at a pumping position in the well casing, said device comprising a plurality of parts connected together for limited relative axial motion, and said unit comprising an expandable packer and a cooperating mandrel having a releasable left-hand screw connection with the lowermost of said parts.

4. In an apparatus for flowing an oil well through the well casing, the combination of a casing pump unit including means to anchor the same at a pumping position in the well casing and means to seal the same within the casing to hold a column of oil above the unit, an insert device connectable with said unit to be turned in one direction to operate said anchor means and movable axially to operate said sealing means, and complementary means on said device and said unit for disconnecting the same when the unit is anchored and sealed and the device is turned in the other direction.

5. In an apparatus for flowing an oil well through the well casing, the combination of a casing pump unit including means to anchor the same at a pumping position in the well casing and means to seal the same within the casing to hold a column of oil above the unit, an insert device connectable with said unit to be turned in one direction to operate said anchor means and movable axially to operate said sealing means, and complementary means on said device and said unit for disconnecting the same when the unit is anchored and sealed and the device is turned in the other direction, the complementary means on said unit comprising a part mating with a part of said sealing means.

6. In an apparatus for flowing an oil well through the well casing, the combination of a casing pump unit including a standing valve, a pump barrel thereabove and a pump head above the barrel including an expandable packer and a tapered hollow mandrel to expand and seal the packer, a string of rods, an insert device interconnecting the mandrel with the string of rods and movable with the rods to position and thereafter seal the unit in the casing, and complementary screw means respectively on said device and said mandrel for disconnecting the rods and insert device from the unit when the unit has been positioned and sealed in the casing.

7. In an apparatus for flowing an oil well through the well casing, the combination of a casing pump unit including a standing valve, a pump barrel thereabove and a pump head above the barrel including an expandable packer and a tapered hollow mandrel to expand and seal the packer, a string of rods, an insert device interconnecting the mandrel with the string of rods and movable with the rods to position and thereafter seal the unit in the casing, and complementary left-hand screw means respectively on said device and said mandrel for disconnecting the rods and insert device from the unit when the unit has been positioned and sealed in the casing, said device comprising an upper part secured to one of the rods, a lower part carrying the screw

means and a slip joint permitting limited relative axial motion between said parts.

8. In an apparatus for flowing an oil well through the well casing, the combination of a casing pump unit including a standing valve, a pump barrel thereabove and a pump head above the barrel including an expandable packer and a tapered hollow mandrel to expand and seal the packer, a string of rods, an insert device interconnecting the mandrel with the string of rods and movable with the rods to position and thereafter seal the unit in the casing, said insert device comprising telescoping tubular members having a tongue and slot connection for limited relative axial motion, and complementary screw means respectively on the lowermost member of said device and on said mandrel for disconnecting the rods and insert device from the unit when the unit has been sealed in the casing.

9. In an apparatus for flowing an oil well through the well casing, a well casing, a nipple through which oil is drawn into the casing, a standing valve connected above this nipple, a pump barrel extending above said standing valve, a pump element attached to a string of rods and carrying a suitable traveling valve and fitting the barrel, a drain sleeve connected with the top of the barrel having an annular expandable packer at its top and a drain tube extending inside the drain sleeve and connected therewith for relative axial movement, and a mandrel element secured to the top of the drain tube having a tapered surface to expand the packer against the well casing, said mandrel being hollow and open at the top to permit free passage therethrough of said pump element.

10. Apparatus for insertion in an oil well casing comprising the combination of tubing having a tubular anchor, packer and mandrel element, the mandrel element movable axially relative to the packer, with an insert device separably connected with said mandrel element and adapted for lowering and fixing said tubing in the well casing, said device having relatively reciprocable parts, means respectively operable by turning said device in one direction and by relatively reciprocating said parts to activate said anchor and to seat said mandrel element into said packer so as to seal the latter at a desired position against the well casing, and means responsive to turning of said device in the other direction when the tubing has been so fixed for disconnecting the device from said tubing at said mandrel element.

11. Apparatus for inserting and sealing in an oil well casing tubing means having an annular expandable packer at its upper end, comprising interconnected upper and lower parts adapted to pass freely through the casing, a slip joint between said parts permitting axial reciprocation of one part relative to the other, means on said upper part for securing it to a string of rods, complementary separable upper and lower elements carried by said lower part, said lower element being hollow and having a tapered outer surface to serve as a mandrel for expanding said packer, mating means on said elements to prevent relative turning but allow relative axial motion therebetween, and screw-threaded means on said lower part and said elements separably interconnecting said elements.

12. Apparatus for inserting and sealing in an oil well casing tubing means having an annular expandable packer at its upper end, comprising interconnected upper and lower parts adapted to pass freely through the casing, a slip joint be-

tween said parts permitting axial reciprocation of one part relative to the other, means on said upper part for securing it to a string of rods, complementary separable upper and lower elements carried by said lower part, said lower element being hollow and having a tapered outer surface to serve as a mandrel for expanding said packer, mating means on said elements to prevent relative turning but allow relative axial motion therebetween, and screw-threaded means on said lower part and said elements separably interconnecting said elements, said upper element comprising a hollow cap, the end of said lower part extending freely through an opening in said cap, and said screw-threaded means comprising registering internal screw threads inside said mandrel element and said cap and a coupling member inside the same on said end having external screw threads engaging said internal threads, said cap receiving said coupling member upon rotation thereof with said parts so as to disconnect said mandrel element.

13. In an apparatus for flowing an oil well through the well casing, comprising a standing valve, a pump barrel extending thereabove, a drain sleeve connected with the top of the barrel having an annular expandable packer at its top and a drain tube extending inside the drain sleeve and connected therewith for limited relative axial movement, a mandrel element secured to the top of the drain tube having a tapered surface to expand the packer against the well casing and being hollow and open at the top to provide passageway for a pump element fitting the pump barrel, and means including screw threads and an axial abutment on said element at its top for separably connecting it with an insert device.

14. Oil well casing pump apparatus comprising the combination of a tubing unit having an anchor, a mandrel and a packer with an insert device separably connected with the mandrel and adapted for positively connecting the unit with a string of rods, said device having relatively reciprocable parts, means respectively operable by turning said device in one direction and by relatively reciprocating said parts to locate and anchor the unit in the well and to set the mandrel into the packer so as to seal the latter at a desired position in a well casing, and means responsive to turning of the device in the other direction when the unit has been so located and sealed for disconnecting the device from the unit.

15. In apparatus for flowing an oil well through the well casing, the combination of a casing pump unit including a standing valve, a pump seat thereabove, a pump barrel above the seat, means to anchor the unit at a pumping position in the well casing, and means to seal the casing to hold a column of oil in the casing, an insert device connectable with the unit adapted to be turned in one direction to operate the anchoring means and to be moved axially thereafter to operate the sealing means, and complementary means on said device and said unit for disconnecting the same when the unit is anchored and sealed and the device is turned in the opposite direction, said unit when the device is disconnected being open at the top and providing an axial passageway therethrough.

16. In combination with a casing pump apparatus including a pump barrel having a standing valve therebelow, a drain sleeve having an expandable packer at the top, tubular means including a pump anchoring device connecting the drain sleeve with the top of the barrel, and a

drain tube extending inside the drain sleeve and connected therewith for limited axial movement, a mandrel element secured to the top of the drain tube having a tapered surface to expand and seal the packer against the well casing and being hollow and open at the top to provide passageway, a cap for said element, cooperating means on said element and said cap to prevent relative turning motion yet permit relative axial motion therebetween, registering female screw threads inside said element and said cap, and an externally threaded coupling member inside said cap engaging said screw threads and having a stem extending through and beyond said cap.

17. In combination with a casing pump apparatus including a pump barrel having a standing valve therebelow, a drain sleeve having an expandable packer at the top, tubular means including a pump anchoring device connecting the drain sleeve with the top of the barrel, and a drain tube extending inside the drain sleeve and connected therewith for limited axial movement, a mandrel element secured to the top of the drain tube having a tapered surface to expand and seal the packer against the well casing and being hollow and open at the top to provide passageway, a cap for said element, cooperating means on said element and said cap to prevent relative turning motion yet permit relative axial motion therebetween, registering female screw threads inside said element and said cap, an externally threaded coupling member inside said cap engaging said screw threads and having a stem extending through and beyond said cap, and an operating member connected with said stem for limited axial movement with respect thereto and adapted to be secured to a string of sucker rods.

18. A mandrel for locating and sealing in an oil well casing tubing means having an annular expandible packer at its upper end, comprising a lower element having a tapered outer surface adapted to move into and expand the packer against the well casing and being hollow and open at the top to provide a passageway, a hollow cap fitting the top of said element, mating means on said cap and said element to prevent turning but allowing axial motion of the cap relative to said element, registering left hand internal screw threads inside said element and said cap, and a coupling member inside the same having external screw threads engaging said internal screw threads to connect the cap and element separably together, said coupling member carried on a stem extending freely through an opening in the cap and said cap formed to receive said coupling member upon turning said stem so as to disconnect said lower element.
